MECHANISM FOR TREATING WIRE ROPE

Henry J. Mische, Belleville, N. J., assignor to
 American Chain & Cable Company, Inc.,
 Bridgeport, Conn., a corporation of New York

Application July 7, 1943, Serial No. 493,798

4 Claims. (Cl. 153—32)

This invention relates to mechanism for treating wire, wire strands, wire cable, and wire rope.

Various ropes or the like as they come off the rope making machine possess residual, torsional, and bending stresses due to the method employed. Devices have been provided for removing these stresses from regular-lay ropes by drawing the rope through offset rolls, sufficiently offset to subject component wires to a bending stress which coupled with the tensile stresses from drawing the rope through the rolls, exceeds the elastic limit. This is done to give the component wires a permanent set tending to make them lie inert in the rope.

I am familiar with machines which comprise a set of offset rolls offset in a single plane and at least another set of offset rolls also offset in a single plane but which extends at right angles to the plane of the first set. These machines include provision for changing the amount of offset between the rolls requiring as many adjustments as there are rolls in the several sets. These adjustments must be made with care. Furthermore no provision is made in these machines for adjusting the rolls relatively in the direction of the travel of the rope and it is practically impossible to use rolls of sufficiently small diameter and sufficiently closely spaced as required for best performance when the machine is to be used for treating very small diameter wires, wire strands, wire cables, or wire ropes.

Among the objects of my invention is the provision of a wire, strand, cable, or rope treating mechanism which is inexpensive to construct and in which the offset bending elements may be closely spaced and readily adjustable in the direction of the travel of the rope, etc. and also at right angles to the travel of the rope and in which many of these elements may be arranged in a small space and in which provision is made for adjusting such elements to bring any part thereof into functioning position. In the accomplishment of these objects I employ two helices in each set of rope treating devices which have their convolutions intermeshed to such an extent as to provide an opening between the opposed inner faces of the respective convolutions of the helices to receive a wire, strand, cable, or rope to be straightened with provision for changing the amount of intermesh and with provision for changing the pitch of the helices.

Other objects of this invention will appear from the following description taken in connection with the drawing, in which—

Fig. 1 is a top plan view of one embodiment of my invention;

Fig. 2 is a side elevational view looking upwardly in Fig. 1; and

Fig. 3 is an end elevational view looking toward the left in Fig. 1.

For the purpose of disclosure I have shown a preferred embodiment of my invention as comprising a supporting base 5 on which are mounted 10 two sets of straightening devices A and B disposed at right angles with respect to each other as indicated in the drawing.

The straightening device A comprises two intermeshed helices 7 and 8 preferably of opposite turn. The helices may be of spring material and normally cylindrical. The helix 7 is supported on a bracket 9 secured to the base 5 by screw bolts as indicated in Fig. 3. This helix is preferably secured to the bracket 9 by means of 15 a clamping plate 10 provided with threaded studs or bolts 11 extending through the bracket and equipped with nuts 12 for drawing the clamping plate toward the bracket. As indicated in Fig. 1 the clamping plate is longer than the helix 7 providing for an axial extension or contraction of the helix for the purpose of adjusting the longitudinal spacing of the parts of the convolutions which engage and treat the rope.

The helix 8 is similarly supported on a bracket 30 14 the base of which is provided with slots 15 receiving threaded bolts 16 which are threaded into the base 5 so as to provide means for adjusting and varying the distance between the axes of the helices 7 and 8 to adjust the amount of 20 intermesh of the helices and the amount of offset of the rope treating parts of the convolutions of the respective helices.

The rope treating device B is of substantially the same construction as that of the device A. 40 It includes the helices 17 and 18. The helix 17 is directly secured to the base 5 by a clamping plate 10. The helix 18 is secured by means of a clamping plate 10 to the horizontal portion 19 of an L-shaped bracket whose vertical portion 10 45 is slotted as indicated at 21 to receive bolts 22 extending through the upwardly extending portion 23 of an L-shaped bracket, the base 24 of which is secured to the base 5 by screw threaded bolts 25 as indicated. The bolts 22 are provided 50 with nuts 26 by means of which the helix 18 may be held in adjusted relation with respect to the helix 17 and the operative and functioning parts of the convolutions to the respective helices held offset the desired amount.

55 The helices provide transversely extending

cushioned working elements which have opposite-
ly facing concave working faces which function
to center the rope as it is drawn through the
devices. The helices may be rotated to present
new parts to the rope in case of wear. The off-
set relation of the operative or functioning parts
of the helices may readily be changed as found
desirable for different diameter ropes and de-
grees of bending necessary to straighten the rope
and to render it inert. The longitudinal spac-
ing of the operative or functioning parts may
readily be adjusted by clamping the helices in
position when stretched or compressed the de-
sired amount. The use of helices of opposite
turns provides a construction in which the oper-
ative or functioning parts of the convolutions of
the helices lie in parallel planes.

Instead of employing helices of small pitch and
closely spaced convolutions as disclosed I may
use helices of greater pitch and space the helices
laterally. By using intermeshed helices of closely
spaced convolutions the rope will be worked
by transverse compression not only as it is drawn
over the inner faces of the convolutions but also
as it is drawn between the adjacent side faces
of the closely spaced adjacent convolutions of the
respective helices.

For convenience of claiming any invention, I
employ the term "rope" in a generic sense to
cover ropes, cables, strands, wires, etc. which may
be straightened in the apparatus of my invention.

While I have illustrated and described with
particularity what I regard as the best form of
one embodiment of my invention, it is to be
understood that I reserve the right to all such
changes and embodiments as fall within the

principle of this invention and the scope of the
appended claims.

I claim:

1. A straightening mechanism comprising two
sets of parallel helices with the convolutions of
each set intermeshed to an extent to provide
an interior opening between their inner opposed
faces to receive a wire rope to be straightened
and with the axes of all the helices parallel, the
common axial plane of one set being disposed at
right angles to that of the other set and the
openings between the convolutions of the sets
lying in the same line.

15 2. A wire rope treating mechanism for render-
ing wire rope inert, comprising a pair of parallel
helices intermeshed to provide between their
overlapped portions a tortuous path for the wire
rope, and means for adjusting the distance be-
tween the axes of said helices and for holding
20 said helices in fixed spaced relation to each
other.

25 3. A wire rope treating mechanism for render-
ing wire rope inert, comprising a pair of parallel
cylindrical helices intermeshed to provide be-
tween their overlapped portions a tortuous path
for the wire rope, and means for securing said
helices in any rotated position and in fixed spaced
relation to each other.

30 4. A wire rope treating mechanism for render-
ing wire rope inert, comprising a pair of parallel
helices intermeshed to provide between their
overlapped portions a tortuous path for the wire
rope, said helices being elongatable and contract-
ible and means for securing said helices in elon-
gated, contracted and normal conditions and in
35 fixed spaced relation to each other.

HENRY J. MISCHE.
